CLAIM

The ornamental design for an oral cleaning tool, as shown and described.

DESCRIPTION

FIG. 1 is a front elevational view of an oral cleaning tool showing my new design;

FIG. 2 is a rear elevational view thereof;

FIG. 3 is a left side view thereof;

FIG. 4 is a right side view thereof;

FIG. 5 is an enlarged top plan view thereof;

FIG. 6 is an enlarged bottom plan view thereof;

FIG. 7 is a perspective view thereof; and,

FIG. 8 is another perspective view thereof.
